BUNG

Louis C. Kappes and Lyall F. Whitney, Cincinnati, Ohio, assignors to Whitney-Kappes Co., Cincinnati, Ohio, a partnership

Application November 28, 1950, Serial No. 197,936

4 Claims. (Cl. 217—109)

1

This invention relates to a bung and more particularly to that class of bung wherein rubber or similar material is compressed so as to expand laterally in order to make sealing contact with the side walls of an aperture. Such bungs are used particularly in connection with beer barrels which may be of wood or aluminum or other material.

It is an object of the present invention to provide a bung of extremely simple construction which will be inexpensive to manufacture and which will perform its purpose efficiently. It is another object of the present invention to provide such a bung which will be neat in appearance and which may be easily applied and removed when desired.

It is yet another object of the invention to provide in association and combination with such a bung a seal member which can be applied to the bung after it has been secured in place in the barrel to prevent tampering with the bung and to indicate positively when the bung has been tampered with.

These and other objects of the invention which will be set forth in more detail hereinafter or which will be apparent to those skilled in the art upon reading these specifications we accomplish by that certain construction and arrangement of parts of which we shall now describe an exemplary embodiment.

Reference is now made to the drawings forming a part hereof and in which:

Figure 1 is a plan view of a bung according to our invention.

Figure 2 is a cross sectional view of the same taken on the line 2—2 of Figure 1.

Figure 3 is an exploded view similar to Figure 2.

Figure 4 is a fragmentary cross sectional view of a wooden barrel showing the bung according to our invention in place.

Figure 5 is a plan view of Figure 4, and

Figure 6 is a fragmentary view of a metal barrel showing how the bung of our invention is used.

Briefly, in the practice of our invention we provide a bung comprising a body and a pressure plate, the body being embraced by alternate rubber-like gaskets and shims and the pressure plate being arranged to bear against said gasket and shims, together with means for squeezing said pressure plate and body together. The two above mentioned parts are squeezed together by means of a threaded stud secured to the pressure plate and extending through an aperture in the body and a nut arranged to engage the threaded stud. We also provide means in the nature of a seal to

2

be fitted over the combined stud and nut within the body to prevent unauthorized tampering with the nut.

Referring more in detail to the drawings, the body is indicated at 10 and the pressure plate at 11. These parts are made of suitable metal and may be extruded in a die. The body member 10 is provided with a central aperture 12 and has the more or less cylindrical body portion 13 and 10 an outwardly extending flange 14. The body portion 13 may have a slight curvature imparted to it as shown, but it may, as well, be perfectly cylindrical.

The pressure plate is also provided with a central hole into which is fitted a stud 15 threaded as at 16 and provided with a flange 17. Beyond the flange 17 the stud is provided with an upstanding collar 18 indicated in broken lines in Figure 3 having an external diameter to pass 15 through the hole in the pressure plate 11 and the upstanding collar 18 is then swaged over as indicated at 19 to lock the stud securely to the pressure plate 11. Sealing engagement of the bung with the walls of the aperture in which it is placed is accomplished by a series of gaskets 20a, 20b and 20c. The gaskets 20a and b are spaced by the shim 21a and the gaskets 20b and 20c are spaced by the shim 21b. It will be observed that the gasket 20a is largest in diameter; the gasket 20b is slightly smaller; and the gasket 20c is still smaller. Similarly the shim 21b is smaller than the shim 21a, while their internal diameters, that is, the internal diameters of all gaskets and all the shims is substantially equal. When the gaskets 20a, b and c and the shims 21a and b are assembled as shown over the body portion 13 of the body member 10 and the pressure plate 11 is applied a washer 22 is placed over the stud 15 and a nut 23 is engaged with the threads 16. The assembled bung is shown most clearly in Figure 2.

It will be clear that when the nut 23 is tightened on the stud 15 the pressure plate will be drawn up against the assembled shims and gaskets which will thus be compressed between the flange 14 of the body portion 10 and the pressure plate 11. In being compressed, the individual gaskets 20a, 20b and 20c are caused to expand radially into sealing engagement with the inner surface of the aperture in which the bung is placed. It will be understood that with the tapered configuration of the assembled gaskets which are arranged to conform to the taper in the aperture or bung hole of the conventional barrel equal sealing contact is attained with each

of the gaskets 28a, 28b and 28c and therefore the bung according to our invention is enabled to withstand very great pressures. As a matter of fact, we have determined that, as tightened with an ordinary socket wrench into a barrel subjected to an internal pressure of one hundred fifty pounds per square inch, the bung remained absolutely secure, even when the barrel was dropped from a height of ten feet or more.

In Figure 4 we have shown a portion of a conventional barrel at 25 and, as is usual in such cases, the bung hole is constituted by an externally threaded, internally tapered bushing member 26. The member 26 is threaded into the side wall of the barrel and remains a part of the barrel.

In Figure 6 we have indicated a fragment of a conventional metal barrel at 27 and have indicated how a portion of the wall of the barrel is thickened as at 28 to provide for the bung hole 29. The bung shown in Figure 6 is identical with that shown in Figure 2. Similarly the bung in Figure 4 is also identical to that shown in Figure 2.

In Figure 4 we have shown in broken lines a sealing member or cap 30. This member may be made of relatively thin inexpensive metal and may bear an imprint of a date as shown in Figure 5. The member 30 is pressed into position as shown in solid lines in Figure 4 over the nut 23 and it is of such size that it must be forced into position. When once in position it cannot be removed without destroying it. For example, in order to remove the seal 30 it may be necessary to puncture it with an ice pick or a can opener or a similar instrument in order to gain access to the nut 23 when it is desired to remove the bung for washing. As long as the seal or cap member 30 is in position as shown in solid lines in Figure 4 and as shown in Figure 5 it is evident that the keg has not been tampered with, and the date on which the keg was filled may be read on the seal. The cap member 30 of course has the additional function of keeping dirt, dust and gritty particles away from the nut 23 and the threads 16 so that the life of the bung is enhanced. As seen in Figure 4, it will be noted that the conformation of the sealing member 30 is such that it fits snugly within the slightly curved body wall portion 13 of the body member 10. Thus the lower rim of the sealing cap 30 must be slightly compressed in order to be seated in the position of Figure 4. This will insure that it will not readily be unseated and that it cannot be pulled out manually. If the body wall 13 is cylindrical, then of course reliance must be had upon a tight press fit of the cap 30.

It will be clear that numerous modifications may be made without departing from the spirit of our invention. We therefore do not intend to limit ourselves in any way other than as set forth in the claims which follow.

Having now fully described our invention, what we claim as new and desire to secure by Letters Patent is:

1. A bung for sealing a container opening comprising a cup-like flanged body member having a central aperture, a pressure plate provided

with a central threaded stud passing through said aperture, a plurality of rubber-like gaskets embracing said body member between said flange and said pressure plate, a substantially rigid metallic shim between each two adjacent gaskets, and a nut engaging said threaded stud by means of which said individual gaskets may be compressed and caused to expand radially to seal said container opening, all of said gaskets and shims having substantially the same inside diameter, but the outside diameters being of progressively different size, whereby upon insertion of said bung in a tapered container opening and tightening of said nut, the individual gaskets make substantially uniform and equal sealing contact with said tapered opening.

2. In combination with the structure of claim 1, a destructable sealing cap having an outside diameter slightly larger than the inside diameter of said cup-like body member, and of a height slightly greater than said nut, but less than the depth of said cup-like body member, said cap being pressed into position within said cup-like body member, covering and protecting said nut.

3. The structure of claim 1 wherein the inside diameter of said cup-like body is greater at its bottom than at its open top, in combination with a destructable sealing cap having an outside conformation complementary to that of the inside wall of said cup-like body, and of a height slightly greater than said nut, but less than the depth of said cup-like body said cap being pressed into position within said cup-like body member, covering and protecting said nut.

4. The structure of claim 1 in which all of said gaskets and shims have substantially the same inside diameter but wherein the outside diameters are of progressively different size whereby upon insertion of said bung in a tapered container opening and tightening of said nut, the individual gaskets make substantially uniform and equal sealing contact with said tapered opening, and wherein the inside diameter of said cup-like body is greater at its bottom than at its open top, in combination with a destructable sealing cap having an outside conformation complementary to that of the inside wall of said cup-like body and of a height slightly greater than said nut, but less than the depth of said body, said cap being pressed into position within said cup-like body member, covering and protecting said nut.
